IRONING MACHINE

Fred A. Conterman, Jamestown, N. Y., assignor to
 Blackstone Manufacturing Company, Inc.,
 Jamestown, N. Y., a corporation of New York

Application November 4, 1937, Serial No. 172,774

5 Claims. (Cl. 38—61)

This invention relates to an improvement in ironers and more particularly to the drive and clutch mechanism thereof.

The present invention is directed to the provision of an improved drive and clutch mechanism for an ironing machine comprised of relatively few elements. This reduction in the number of elements is possible through the elimination of eccentric shafts, special gearing, etc. The enclosure for a mechanism of this nature is therefore comparatively small and occupies only a small part of the work table of the device. Furthermore, through the elimination of a multiplicity of gears and the provision of only one main rotational center, manufacturing and installing costs are extremely low.

One of the more important objects of the invention lies in the provision of a drive and clutch mechanism for an ironer which is of simple construction and easily and quickly operated for the purpose of controlling rotation of the ironing roll and movement of the ironing shoe.

Another object of the invention lies in the provision of a station and roll clutch mechanism which rotates about one center thus greatly reducing the size and number of parts therefore.

Another object of the invention lies in the provision of a device of this class which, due to the few elements of which it is comprised, is inexpensive to manufacture and easy to assemble.

Other and further objects and advantages of the invention will be more fully understood from a consideration of the following specification taken in conjunction with the accompanying drawings and in which—

Fig. 1 is a perspective view of an ironing machine embodying one modification of the invention;

Fig. 2 is an enlarged fragmentary plan view of the drive and clutch end of the machine shown in Fig. 1, parts of the casing being broken away to disclose details of the mechanism;

Fig. 3 is an enlarged vertical sectional view of the machine, being taken substantially on the line 3—3 of Fig. 2, and shows the ironing shoe in position for use;

Fig. 4 is an enlarged vertical sectional view taken substantially on the line 4—4 of Fig. 5;

Fig. 5 is an end view of the drive and clutch mechanism, being taken substantially on the line 5—5 of Fig. 2, parts being broken away to disclose the roll release;

Fig. 6 is a fragmentary vertical sectional view taken substantially on the line 6—6 of Fig. 5

and shows the mounting means for the ironing shoe;

Fig. 7 is an end view of the clutch mechanism showing the ironing shoe in released or opened position;

Fig. 8 is a further end view of the clutch mechanism showing the clutch engaged to move the ironing shoe into position for use;

Fig. 9 is a further end view of the clutch mechanism and shows the ironing shoe in position for use and the clutch mechanism about to be disengaged;

Fig. 10 is an end view of the clutch mechanism after it has disengaged and the ironing shoe is in position for use; and

Fig. 11 is a fragmentary view showing the shoe mounting means and the clutch operated eccentric for moving the shoe.

Reference is now had to the drawing wherein the numeral 10 is employed to generally designate an ironing machine. The machine comprises legs 11, table top 12, and drop leaf 13. Conveniently located beneath the top 12 is an electric motor 14 which, through a pulley, is connected by a belt 16 with a gear and clutch 25 mechanism located at one end of the top 12 and enclosed by a casing 17. The casing 17 is preferably a casting and includes a base wall 18, end walls 19 and 21 and side wall 22. The other side wall 23 takes the form of a cover plate 30 which gives access to the interior of the casing. The end wall 19 is curved at its upper end and meets a correspondingly curved portion of the other end wall 21 which is formed with an offset extension 24 for the purpose of enclosing a portion of the mechanism hereinafter described. Projecting laterally from the side wall 22 is a flange 26 which, when closed by a cover plate 27, provides an enclosure for a pulley 28. To one side and directly above the flange 26, two bosses 40 and 31 are formed in the wall 22 of the casing. The lower portion of the boss 29 is formed with an opening 32 in which is located a sleeve 33. At one end the sleeve 33 terminates flush with the end of the boss 29 and at the other end 45 lies within the casing 17. Mounted on the end of the sleeve 33, lying within the casing 17, is a gear 34 having teeth 36. A small gear 37 meshes with the teeth 36 of the gear 34 and is mounted on a shaft 38 which projects through wall 22 of the casing into the space defined by the flange 26 and cover 27. The pulley 28 is located within this space and keyed to this shaft. The belt 16, which is driven by the motor 14, engages the pulley 28 and the entire driving mechanism of

the device functions through gears 37 and 34.

Located within and adjacent the ends of sleeve 33 is a pair of oilless bushings 39 which serve to mount a shaft 40 out of contact with the sleeve. One end of this shaft projects beyond the boss 29 and is fitted with a gear 41. The other end of the shaft 40 projects into the casing 17 and beyond the gear 34 is splined as at 42. The boss 29 is formed with a further opening 43, located above the opening 32, which connects the interior of the casing 17 with the exterior. Within the opening 43 is a tube 44 that serves as a shaft to mount an ironing roll 46. At one end, the roll 46 is supported on the tube 44 by a plate 47, along a flange 48 thereof. Centrally of the plate 47 is an opening in which is fitted a suitable bearing 49. The end of the roll 46, adjacent the casing 17, has an interior member 51 that is formed with an annular collar 52 through which the tube 44 projects. An outer flange 53 of the member 51 is secured to the roll 46 in any suitable manner as by rivets. The inner surface of this flange is formed with teeth 54 which are engaged by the teeth of gear 41 located on the outer end of shaft 40.

Reference is now had to Fig. 6 of the drawings wherein the boss 31 is provided with an opening 57. The boss 31 in cooperation with a bracket 58 supports a tube 59, through which a rod 61 projects. The tube 59 at one end projects into the boss 31 terminating substantially flush with the interior face of the wall 22 and at the other end within the bracket 58. The rod 61 projects into the casing 17 and mounts a rocker arm 62 which lies adjacent the wall 22 and terminates beneath the shaft 40. The outer end of the shaft 61 projects beyond the bracket 58 and is fitted with a presser arm 63. This arm (see Figures 3 and 6) includes a channel member 64 having an interior block 65. A pin 66 keys the block to the shaft 61. The block is formed with a finger 67 that lies adjacent the base wall of the channel and through which is a threaded opening 68. A recess 69 in the block 65 accommodates one end of a leaf spring 71. A screw 72 projects through an opening in the base wall of the member 64 and is engaged with the threads of the opening 68, being adjustable to move into pressure contact with the spring 71 and move the free end thereof into pressure contact with a link 73. The link 73 is mounted on a pin 74, the ends of which are supported on the side walls of the channel member 64. A threaded opening 76 in the link 73 is adapted to receive one end of the shaft 77 to which is affixed a handle or knob 78. An ironing shoe 79 is provided with a recessed bracket 81 in which a portion of the link 73 is positioned. A pivot pin 82 connects the bracket 81 with the link 73. It will be noted that the portion of the link 73 lying within the member 64 is formed with a flat face 83 against which the spring 71 presses when the rod 77 and shoe 79 assume the position shown in Fig. 3. Under normal operation of the machine, shaft 61 is reciprocable and swings the ironing shoe 79 into or out of ironing position. However, in the event the mechanism within the casing ceases to function or for any other reason it is necessary to withdraw the ironing shoe 79 from pressure contact with the roll 46, the knob 78 may be moved rearwardly of the device causing the substantially straight line connection between arm 73 and shoe 79 to be broken and the shoe is thus immediately released.

Within the casing 17, between wall 22 thereof

and gear 34 is an eccentric clutch assembly which comprises a member 84 through which a transverse opening 85 is made. The member 84 is mounted to rotate freely on the sleeve 33. Adjacent one end of the member 84 is an annular shoulder 87 in which is formed a recess for receiving the looped end of a spring 88. The straight portion of the spring projects laterally away from the sleeve 33 and is anchored in a pin 89 secured to the wall 22. Adjacent the shoulder 87 is an eccentric 91. This eccentric is preferably integral with the member 84 and provides an outer surface on which is mounted an eccentric strap 92. The strap 92 includes an arm 93 which is pivotally joined at one end to the rocker arm 62 through a pin 94. In one form the rocker arm 62 is provided with a slot for receiving the arm 93 of the eccentric strap 92. Adjacent the eccentric 91 and also forming a part of the member 84 is a radially extending arm 96. A lug 97 is provided on one face of the arm 96, being drilled to receive a pin 98 which pivotally mounts one end of a dog 99. Another arm 100 projects radially from the center of the member 84 in a direction opposite to arm 96. A small opening 101 is made in the end of this arm for the purpose of securing one end of a spring 102. It will be noted that an annular shoulder 103 is provided at the opposite end of the member 84 from the shoulder 87. This shoulder serves to mount a plate 104. The plate 104 is rotatable about the shoulder 103 within limits herein-after set forth. At opposite ends the plate is provided with fingers 105 and 106. Adjacent the finger 106 the plate is fitted with a pin 107 which projects into a slot 108 in the dog 99. Since one end of the dog 99 is pivotally mounted on the lug 97 of the arm 96 and the other end thereof is limited in movement to the size of the slot 108 and also, the pin 107 is attached to plate 104, it is apparent that movement of the plate will cause the dog to rotate about its pivot 98 in a direction to move a lug 109 on the dog radially toward or away from the axis of rotation of the plate 104. Adjacent the pin 107, the plate 104 is formed with an opening 110 which serves to secure the other end of spring 102. Adjacent the finger 105 is an opening 111 which secures one end of a spring 112. The other end of the spring 112 is joined to the end of the dog 99 adjacent the pivot pin 98. It will thus be noted that movement of the dog about the pivot 98 to move lug 109 radially away from the rotational center of the structure changes the relative position of plate 104 and dog 99 and increases the tension on springs 102 and 112.

Projecting through a suitable supporting lug in the end wall 22 of the casing is a rod 113. On the outer end of the rod is located a control lever 114. The inner end of the rod lying within the interior of the casing 17 is fitted with an arm 115, the end 116 of which takes the form of a finger trip. The arm 115 is normally held in the position shown in Fig. 9 of the drawings by a spring 117.

Formed in the hub of gear 34 are radial teeth 118. It will be noted that the dog 99 is adjacent the surface of plate 104 which is next to the gear 34. Consequently, the dog 99 is in the same vertical plane with the teeth 118 in the hub of the gear 34.

Reference is now had particularly to Figures 4 and 5 of the drawings wherein a mechanism for starting and stopping the roll 46 is shown. The gear 34, which rotates continuously when

the machine is in use, is provided with teeth 119 on that face of the hub opposite to the teeth 118. The shaft 40 within the sleeve 33 projects beyond the hub of gear 34 and is fitted with a clutch throwout member 120. The shaft 40 is splined and the member 120 is rotatable therewith. The member 120 is formed with a series of laterally projecting teeth 121 which, under certain circumstances of operation of the device, mesh with the teeth 119. The member is also formed with an annular groove 122. A bracket 123 is secured to a bottom flange of the casing in any suitable manner as by screws 124. This bracket is provided with upstanding end lugs 125 having openings to receive a shaft 126. The central portion of the shaft 126 is squared and a pair of spaced apart arms 127 are mounted thereon. Adjacent their upper ends, the arms are provided with pins 128 which fit the annular recess 122 of the member 120. The arms 127 terminate in fingers 129. The cover plate 23 of the casing 17 is formed with lugs 131 through openings in which a rod 132 projects. One end of the rod extends beyond an edge of the cover plate and is fitted with a control lever 133. Between the lugs 131 a pair of slots 134 are made in the rod 132 which are in vertical alignment with and adapted to receive the fingers 129 of arms 127.

Secured to the squared portion of the shaft 126 is an arm 136 which terminates in a finger portion 137 that rests on the rocker arm 62. A spring 138 is secured at one end to the rocker arm and at the other may be fastened to one of the screws 124. The purpose of this spring is to cause the finger 137 of the arm 136 to at all times contact the rocker arm 62 and also urge fingers 129 of arms 127 into contact with the flat surfaces of the recesses 134 and the rod 132.

For a clearer understanding of the invention 40 the description of the operation thereof commences with the ironing shoe 79 in open position and the elements of the drive and clutch mechanism in the position shown in Figure 7 of the drawings. It will be understood that during use of the ironing machine the motor 14 runs continuously and, through belt 16, rotates pulley 28, shaft 38, and gear 34. Until such time as the shoe 79 is to be moved into operative position and the roll 46 rotated, gear 34 rotates freely 45 about sleeve 33. The lever 114 serves to control the ironing shoe 79 and allow it to move into pressure contact with the roll 46. When this lever is depressed, arm 115 is swung upwardly causing the portion 116 thereof to disengage the 50 finger 105 of the plate 104. Attention is directed to the fact that so long as the portion 116 engages finger 105, the relative position of the dog 99 and plate 104 remains as shown in the drawings. This is due to the fact that the spring 88 which encircles the member 84 has a frictional 55 contact therewith and tends to rotate with any attempted rotation of this member. The end of this spring, however, is anchored against such rotation and thus member 84 can only rotate 60 against a frictional wrap around tension of the spring in this direction. Inasmuch as the spring 88 is stronger than either or both springs 102 and 112, the slotted end of the dog is swung away 65 from the sleeve 33 and the lug 109 thereby remains out of mesh with the teeth 118 in the hub of the gear 34.

Immediately the portion 116 is withdrawn from the finger 105, the tension of the spring 102 is released and the plate 104 is caused to rotate 70 slightly about the member 84. This movement

causes pin 107 to swing the slotted end of the dog inwardly moving the lug 109 into mesh with the teeth 118. This position of the elements of this portion of the mechanism is clearly shown in Figure 8 of the drawings. Gear 34 is thus caused 5 to rotate member 84, plate 104, and dog 99. The eccentric 91 on the member 84, on which the eccentric strap 92 is mounted, is thereby caused to rotate. At the commencement of this operation it will be understood that the eccentric strap 10 92 was in raised position and through its connection with the rocker arm 62 maintained the ironing shoe 79 in inoperative position. Rotation of the eccentric 91 one hundred eighty degrees, moves the eccentric strap 92 downwardly 15 through the position shown in Figure 8 to substantially that of Figure 9. Finger 106 now comes into position and is engaged by the portion 116 of the arm 115 and further rotation of the member 84, plate 104 and dog 99 is thus prevented. 20 Again due to the frictional engagement of the spring 88 with the member 84, the dog 99 and plate 104 are caused to have relative movement and assume the position shown in Figure 10. At this point the ironing shoe is in operative position. 25

During the one hundred and eighty degree rotation of the above mechanism, the eccentric strap 92 has moved rocker arm 62 downwardly and arm 136 has rotated about shaft 126 by reason of the tension of spring 138. Since shaft 30 126 has been caused to rotate, arms 127 have moved laterally causing the member 120 to move along shaft 40 and the teeth 121 thereof to interengage the teeth 119 located on the hub of the gear 34. Rotation of shaft 40 causes the roll 35 46 to rotate through engagement with teeth 54 of the member 51.

When it is desired to release the ironing shoe 79 and stop rotation of the roll 46, the lever 114 is again depressed to raise the arm 115 and release finger portion 116. The dog 99 again engages the teeth 118 on gear 34 and this portion of the structure rotates until finger 105 again strikes the portion 116 of arm 115 and the elements are in the position shown in Figure 7, and the ironing shoe is in inoperative position. During the process of opening the ironing shoe, rocker arm 62 has swung upwardly causing arm 136 to move upwardly and moving arms 127 laterally to disengage the teeth 121 of the member 120 50 from the teeth 119 of the gear 34. Disengaging these sets of teeth stops rotation of the shaft 40 and roll 46.

It is sometimes found desirable to press an article in a device of this class by simply moving the ironing shoe into contact with the roll when not in motion and since rotation of the roll of this device is made automatic with the operation of the ironing shoe, an auxiliary structure is provided in the form of the lever 60 133. When this lever is rotated from a horizontal to a vertical position, the shaft 132 is rotated. The edges of the slots 134 contact the fingers 129 of arms 127 moving said arms laterally to disengage the teeth 121 of member 120 65 from the teeth 119 of the gear 34. When it is desired that the machine again operate in the usual manner the lever 133 is moved into the position shown in Figures 1 and 2 of the drawings and rotation of the roll again becomes 70 automatic.

Although applicant has shown and described only one modification of his invention in connection with an ironing machine, it will be apparent to those skilled in the art that variations 75

or adaptations of the structure herein shown and described may be made without departing from the spirit and scope of the invention as defined in the hereunto annexed claims.

5 Having thus set forth my invention what I claim as new and for which I desire protection by Letters Patent is:

1. In an ironing machine having a rotatable ironing roll and an ironing shoe movable into 10 pressure contact with the roll, a mechanism for driving said roll and actuating said shoe comprising a gear having permanent connection with suitable motive means, a sleeve mounting said gear, a rotatable shaft in said sleeve, gear 15 means connecting said shaft with said roll, a clutch on said shaft, said clutch being adapted to couple said shaft with said driven gear, a combined station clutch and eccentric mounted on said sleeve, means connecting said eccentric with said ironing shoe, 20 said station clutch being operable to engage said driven gear and transmit motion through said eccentric to said shoe.

2. In an ironing machine having a rotatable ironing roll and an ironing shoe movable into 25 pressure contact with the roll, a mechanism for driving said roll and actuating said shoe including a gear having permanent connection with suitable motive means, a sleeve mounting said gear, a rotatable shaft in said sleeve, gear means 30 connecting said shaft with said roll, a clutch on said shaft, said clutch being operable to couple said shaft with said driven gear, a combined station clutch and eccentric mounted on said sleeve, means connecting said eccentric with 35 said ironing shoe, said clutch being operable to engage said driven gear and transmit limited motion through said eccentric to said shoe.

3. In an ironing machine having a rotatable ironing roll and a movable shoe movable into 40 pressure contact with the roll, a mechanism for driving said roll and actuating said shoe comprising a gear having permanent connection with suitable motive means, a sleeve mounting said gear, a rotatable shaft in said sleeve, gear

means connecting said shaft with said roll, a clutch on said shaft, said clutch being adapted to couple said shaft with said driven gear, a combined station clutch and eccentric mounted on said sleeve, means connecting said eccentric with 5 said shoe, said station clutch being engageable with said driven gear and adapted to transmit motion through said eccentric to said shoe, said means being adapted to actuate the clutch on said shaft during movement of said shoe. 10

4. In an ironing machine having a rotatable ironing roll and an ironing shoe movable into pressure contact with the roll, a mechanism for driving said roll and actuating said shoe, said mechanism being operable about a common 15 rotative axis and comprising a continuously driven gear, a sleeve mounting said gear, a rotatable shaft in said sleeve, said shaft terminating beyond the ends thereof, gear means connecting one end of said shaft with said roll, a clutch 20 on the other end of said shaft, said clutch being adapted to couple said shaft with said driven gear, means carried by said sleeve interposed between said gear means and said driven gear, further means for moving said shoe into and 25 out of contact with said roll, said means being operable to contact said driven gear with said shoe means.

5. In an ironing machine having a rotatable ironing roll and an ironing shoe movable into 30 pressure contact with the roll, a mechanism for driving said roll and actuating said shoe comprising a continuously driven gear, a sleeve mounting said gear at one end thereof, a shaft projecting through and beyond the ends of said 35 sleeve, means connecting said shaft with said roll, a clutch operable to connect said driven gear with said shaft, and means carried by said sleeve operable to engage said driven gear, said means also having connection with said shoe 40 and serving to transmit motion of said gear to said shoe.

FRED A. CONTERMAN.
